[57] CLAIM

The ornamental design for a handle for a screwdriver or similar article, as shown and described.

DESCRIPTION

FIG. 1 is a perspective view of a handle for a screwdriver or similar article showing my new design;

FIG. 2 is a right side elevational view thereof;

FIG. 3 is a left side elevational view thereof;

FIG. 4 is a front elevational view thereof; and

FIG. 5 is a rear elevational view thereof.

The broken line portions of the drawing are for illustrative purposes only and forms no part of the claimed design.
